N. Y., a corporation of Delaware

Application March 23, 1949, Serial No. 83,093

7 Claims. (Cl. 179—100.41)

1

This invention relates to electromagnetic recording heads for the recording of sound on records of suitable material. While of general applicability to the field of sound recording, the invention is particularly applicable to the embossing of very fine laterally-modulated sound grooves in film.

Primary objects of the invention are the provision of an efficient recording head of very simple construction which provides high fidelity recording and yet is relatively inexpensive.

The recording head of the present invention is of the variable reluctance type employing two air gaps in the magnetic circuit on opposite sides of the pivot point of the armature. This system is often termed a double-ended armature or balanced armature system. In such recording heads the cross-sectional area of the armature and the pole pieces must be large enough to provide an efficient magnetic path. Also a centering spring system must be provided which is stiff enough to prevent collapse of the armature against a pole due to D.-C. flux produced by the permanent magnet. The mass or moment of inertia of the armature, together with the centering spring system, results in a moving mechanical system having a natural period of vibration. In order to obtain high fidelity response from such a recording head, it is necessary to make this natural period of vibration as high as possible, since the frequency response extends only to a limited extent beyond the peak corresponding to the natural period of vibration, and drops off very rapidly beyond this limited range.

In accordance with the present invention a single coil is utilized and a novel pivot and spring suspension is provided which pivots the armature midway along the axis of the coil without substantially reducing the effective cross-sectional area of the armature and the pole pieces. This novel suspension permits the distance from the pivot point to the air gaps to be reduced to a minimum, thereby reducing the effective mass and moment of inertia of the armature. This reduction in effective mass and moment of inertia is accomplished without reducing the efficiency of the magnetic circuit. As a result, the resonant peak of the armature and suspension is high in the audio range and produces a very high fidelity recording head.

It is also important that the pivot axis of the armature be very rigid so as to prevent any lateral motion of the armature which would amount to lost motion and reduce the efficiency of the head. It is also important that the suspension be simple

2

and rugged, and capable of manufacture with minimum variation in dimensions and tempering.

In accordance with the invention a knife edge is provided midway between the air gaps, and in the center of the coil, so as to provide a fixed rigid pivot axis for the armature. This knife edge allows oscillation of the armature so as to produce lateral movement of the associated stylus, but prevents any lateral movement of the armature as a whole. On the opposite side of the armature a flat spring is provided which bears against the armature at two points evenly spaced on opposite sides of the knife edge to provide equal and opposite torques. This spring is provided with legs which are held in the pole piece on that side of the armature with provision for adjusting the spring tension and for rigidly securing it in its adjusted position.

The invention will be more fully understood by reference to the following detailed description thereof taken in conjunction with the drawings in which:

Fig. 1 is a vertical cross-section taken along the line 1—1 of Fig. 2;

Fig. 2 is a lateral cross-section taken along the line 2—2 of Fig. 3;

Fig. 3 is a horizontal cross-section taken along the line 3—3 of Fig. 2;

Fig. 4 is a bottom view of the recording head;

Fig. 5 is a plan view thereof;

Fig. 6 is a detail showing the knife edge forming the horizontal pivot axis; and

Fig. 7 is a detail showing the spring member.

Referring to the drawings, a top supporting plate 10 of non-magnetic material has affixed thereto, by means of mounting screws 11, a pair of channel pole pieces 13 and 14. The cross-sections of these pole pieces are U-shaped. The sides of the pole pieces are substantially horizontal and the front portions 15 and 16 thereof project inwardly in horizontal alignment to define a pair of air gaps 17 and 18. These air gaps 17 and 18 are separated in a vertical direction and are relatively long in the axial direction and relatively narrow in the lateral direction. A permanent magnet 19 is positioned in abutment with the rear ends of the pole pieces 13 and 14 with the magnetic poles of the magnet adjacent respective pole pieces. The direction of magnetization is indicated by arrow 20. In consequence, a constant D.-C. magnetic field is produced across air gaps 17 and 18 and extends in the same direction across both gaps.

An armature 21 of magnetic material such as soft iron is positioned within the air gaps and has

an axial length substantially the same as that of the air gaps. The vertical height of the armature is substantially the same as that of the pole pieces so that the upper and lower portions of armature 21 are within respective air gaps 17 and 18. The front end of the armature is provided with a downwardly extending leg 22 which carries the recording stylus 23.

The cross-sectional areas of the armature and the edges of the pole pieces forming the air gaps are sufficiently large to form an efficient magnetic circuit.

The armature is held in position by a suspension comprising knife edge 24 on plate 25, and cooperating abutments 26 on spring 27. Plate 25 is secured in a suitable recess in the front portion of pole piece 14 with the knife edge midway between the upper and lower projecting portions of the pole piece. The knife edge is accordingly midway between the air gaps 17 and 18. The knife edge extends in the axial direction and thus allows oscillation of the armature to produce lateral movement of the stylus 23. However, the knife edge is rigidly positioned in the pole piece and provides a rigid pivot axis for the armature. Hence lateral movement of the armature as a whole is prevented, thereby preventing lost motion which would impair the response of the head. Although the knife edge 24 is advantageously broken into two spaced segments as shown, it could be made continuous if desired.

The cooperating spring 27 is bent in the form of a U with a relatively flat spring face 28. Abutments 26, advantageously in the form of short knife edges as shown, project from the face 28 so as to abut the armature at spaced points. Spring 27 may be conveniently formed by flattening the central portion of a round wire, forming the knife edges 26 during the flattening operation, and bending the ends of the wire to form legs 29. The spring may thereafter be hardened and tempered.

The legs 29 of the spring fit into mounting holes in the upper and lower sides of pole piece 13, and centrally located with respect to the corresponding air gaps. When in position, the abutments 26 are parallel to knife edge 24 but are spaced apart in a vertical direction; that is, laterally of knife edge 24, by equal amounts on each side of the latter. Abutments 26 hence apply equal and opposite torques to armature 21 about knife edge 24. Spring 27 is advantageously located so that the center line of abutments 26 is perpendicular to the knife edge 24 at a point midway of the latter. Thus the armature is pressed securely against knife edge 24 and any oscillation or vibration about a vertical axis is prevented.

Adjusting screws 31 bear against the ends of legs 29 and press the spring into engagement with the armature. In the initial assembly the force of the spring on the armature is made sufficient to center the armature in the air gaps and insure that the armature does not collapse against a pole piece due to the D.-C. flux produced by the permanent magnet 19. When the proper tension is obtained, screws 32 are tightened against upper and lower legs 29 to clamp the spring securely in position. It has been found advantageous to locate screws 32 as close as possible to the inner edges of the upper and lower sides of pole piece 13, that is, close to the air gaps, so that spring member 27 is rigidly secured as close as possible to the bends 35. In this way undesired vibrations and spurious response peaks may be avoided.

Suitable V-shaped indentations may be made in armature 21 to cooperate with knife edge 24 and abutments 26.

An actuating coil 33 is positioned within the space between the pole pieces and encircling the armature 21. When energized with sound frequencies through lead 34, the armature is vibrated according to the variable reluctance principle and causes the stylus 23 to move laterally in accordance with the sound frequencies.

It will be apparent that the armature suspension described above serves to provide a pivot axis which is midway between the air gaps and in the center of coil 33, and that the axis of rotation is rigidly established to allow oscillation of the armature about the pivot axis but no movement in any other direction. This is accomplished without increasing the vertical separation of the air gaps over that required to accommodate coil 33. Furthermore, the manner of suspension in no way decreases the effective cross-section of the armature. As a result, the height of the armature is kept to a minimum with consequent low mass and moment of inertia, without decreasing the efficiency of the magnetic circuit. This permits placing the resonant response peak high in the audio range, and therefore enables a high fidelity recording head to be produced.

As an example for purposes of illustration only, the response curve for one recording head made in accordance with the invention showed efficient operation from 20 to 11,000 cycles per second, with the resonant peak at about 9,000 cycles per second. When used for embossing sound grooves in a film of cellulose acetate or other plastic, the damping provided by the recording medium sufficed to damp out this resonant peak and yield a flat response.

Under some conditions of operation the recording medium may not provide sufficient damping to flatten out the resonant peak. This might occur in cutting grooves in lacquer or wax. In such event damping material may be incorporated in the recording head to provide damping of the armature.

It will also be appreciated that the recording head of the invention is very simple and is composed of simple parts which can be readily manufactured and assembled. In particular, the use of a single spring to provide opposing torques about the axis of the knife edge insures proper operation since the forming and tempering may be readily and precisely controlled, and the spring action is uniform at both contacts with the armature. Thus difficulties encountered with the use of two or more springs are avoided.

It will be apparent to those skilled in the art that many details of the specific embodiment described hereinbefore may be modified within the spirit and scope of the invention.

I claim:

- An electromagnetic sound recording head which comprises a pair of U-shaped pole pieces positioned to define a pair of air gaps therebetween, magnet means for producing a magnetic field across said air gaps, an armature positioned within said air gaps and adapted to carry a stylus, a knife edge positioned midway between said air gaps and engaging one side of said armature to provide a pivot axis therefor, a unitary compressional spring member having a pair of abutments engaging the opposite side of said armature at respective points spaced apart laterally of said knife edge and on opposite sides thereof to provide substantially equal and opposite torques on

said armature, and an actuating coil positioned in the space defined by said pole pieces and encircling said armature.

2. An electromagnetic sound recording head which comprises a pair of U-shaped pole pieces disposed with the open ends facing and in substantial alignment to define a pair of air gaps, magnet means for producing a substantially constant magnetic field in the same direction across said pair of air gaps, a flat armature positioned within said air gaps and adapted to carry a stylus, a knife edge positioned midway between said air gaps and engaging one side of said armature to provide a pivot axis therefor allowing oscillation of said armature in said gaps, a unitary compressional spring member having a pair of abutments between said air gaps engaging the opposite side of said armature at respective points spaced apart in a direction lateral of said knife edge and on opposite sides thereof to provide substantially equal and opposite torques on said armature, and an actuating coil positioned in the space defined by said pole pieces and encircling said armature.

3. An electromagnetic sound recording head which comprises a pair of channel pole pieces positioned with the openings thereof facing and the sides thereof in substantial alignment to define a pair of elongated air gaps, magnet means for producing a substantially constant magnetic field in the same direction across said pair of air gaps, a flat armature positioned within said air gaps and adapted to carry a stylus, a knife edge positioned midway between said air gaps and parallel thereto and engaging one side of said armature to provide a pivot axis allowing oscillation of the armature in the air gaps, an elongated unitary spring member positioned on the opposite side of said armature and extending laterally of said knife edge, said spring member having a pair of abutments spaced therealong between said air gaps and bearing against said armature at respective points on opposite sides of said knife edge, and an actuating coil positioned in the space defined by said pole pieces and encircling said armature.

4. An electromagnetic sound recording head which comprises a pair of channel pole pieces positioned with the openings thereof facing and the sides thereof in substantial alignment to define a pair of elongated air gaps, magnet means for producing a substantially constant magnetic field in the same direction across said pair of air gaps, a flat armature positioned within said air gaps and adapted to carry a stylus, a knife edge positioned midway between said air gaps and parallel thereto and engaging one side of said armature to provide a pivot axis allowing oscillation of the armature in the air gaps and resultant lateral movement of the stylus, a unitary spring member extending between the sides of the pole piece on the opposite side of said armature and lateral of said knife edge, said spring member having a pair of abutments between said air gaps spaced apart laterally of said knife edge and bearing against said armature at respective points substantially equally spaced on opposite sides of the knife edge, and an actuating coil positioned in the space defined by said pole pieces and encircling said armature.

5. An electromagnetic sound recording head which comprises a pair of channel pole pieces positioned with the openings thereof facing and the sides thereof in substantial alignment to define

a pair of elongated air gaps, magnet means for producing a substantially constant magnetic field in the same direction across said pair of air gaps, a flat armature positioned within said air gaps and adapted to carry a stylus, a plate mounted between the sides of one of said pole pieces having a knife edge midway between said air gaps and parallel thereto, said knife edge engaging one side of said armature to provide a fixed pivot axis allowing oscillation of the armature in said air gaps, a U-shaped unitary spring member having the legs thereof mounted in respective sides of the other of said pole pieces with the face thereof extending along the other side of said armature substantially perpendicular to said pivot axis, said spring member having a pair of spaced knife edges parallel to the first mentioned knife edge and bearing against said armature at respective points between said air gaps which are equally spaced on opposite sides of said pivot axis along a line perpendicular thereto, and an actuating coil positioned in the space defined by said pole pieces and encircling the armature, the plate bearing the knife edge and the face portion of the spring.

6. An electromagnetic sound recording head which comprises a pair of channel pole pieces positioned with the openings thereof facing and the sides thereof in substantial alignment to define a pair of elongated air gaps, a permanent magnet arranged to create magnetic fields extending in the same direction across said air gaps, a flat armature positioned within said air gaps and having a downwardly extending portion bearing a stylus, a knife edge positioned midway between said air gaps and parallel thereto and engaging one side of said armature to provide a fixed pivot axis allowing oscillation of the armature in the air gaps and resultant lateral movement of the stylus, a U-shaped unitary spring member having the legs thereof mounted in laterally extending holes in respective sides of the other of said pole pieces, the face of said spring member being elongated and substantially flat and extending along the other side of said armature perpendicular to said pivot axis and midway therealong, said spring member having a pair of spaced knife edges parallel to the first-mentioned knife edge and bearing against said armature at respective points between said air gaps which are equally spaced on opposite sides of said pivot axis along a line perpendicular thereto, and an actuating coil positioned in the space defined by said pole pieces and encircling said armature.

7. An electromagnetic sound recording head which comprises a pair of channel pole pieces positioned with the openings thereof facing and the sides thereof in substantially horizontal alignment, the front portions of the sides of said pole pieces projecting inwardly to define a pair of vertically-separated axially-elongated air gaps, a permanent magnet positioned with the magnetic poles thereof adjacent respective rear ends of said pole pieces to create magnetic fields extending in the same direction across said air gaps, a flat armature positioned within said air gaps and having a downwardly extending portion bearing a stylus, a plate mounted between the projecting portions of one of said pole pieces having a knife edge extending parallel to said air gaps and midway therebetween, said knife edge engaging one side of said armature to provide a fixed pivot axis allowing oscillation of the armature in said air gaps, a U-shaped unitary spring member having the legs thereof mounted in laterally extending

holes in respective projecting portions of the other of said pole pieces, the face of said spring member being elongated and substantially flat and extending along the other side of said armature perpendicular to said pivot axis and midway therealong, said spring member having a pair of spaced knife edges parallel to the first-mentioned knife edge and bearing against said armature at respective points between said gaps which are equally spaced on opposite sides of said pivot axis along a line perpendicular thereto, adjusting means engaging the legs of said spring member to adjust the tension thereof against the armature, clamping means engaging said legs near the face of said spring, and an actuating coil positioned in the space defined by said pole pieces and encircling the armature, the plate bearing the knife edge and the face portion of the spring.
